A. R. KAHL.
TELEPHONE TRANSMITTER,
APPLICATION FILED MAR. 20, 1916.

Patented Jan. 21, 1919.

UNITED STATES PATENT OFFICE.

ARTHUR ROBERT KAHL, OF WITHTINGTON, MANCHESTER, ENGLAND.

TELEPHONE-TRANSMITTER.

1,291,911.

Specification of Letters Patent.

Patented Jan. 21, 1919.

Application filed March 20, 1916. Serial No. 85,247.

To all whom it may concern:

Be it known that I, ARTHUR R. KAHL, a citizen of the United States, residing at 59 Burton road, Withington, Manchester, England, have invented certain new and useful Improvements in Telephone-Transmitters, of which the following is a specification.

My invention relates to an improved telephone transmitter construction, in which the main diaphragm is specially shaped and mounted so as to improve the purity of tone of the instrument and eliminate external or picked up noises. Another feature of my improved construction consists in the manner in which the mica diaphragm of the variable resistance element is clamped, as a result of which the operation of the resistance element is much improved.

My invention will be better understood by reference to the drawings in which—

Figure 1 is a longitudinal central sectional view through the transmitter completely assembled, some of the parts being shown in elevation for clearness;

Fig. 2 is a back elevation of the transmitter with the inclosing shell removed;

Fig. 3 is a longitudinal central sectional view through the variable resistance element of the transmitter; and

Fig. 4 shows in elevation a spring clamping disk employed in connection with the variable resistance element construction.

Similar numerals refer to similar parts throughout the several views.

The transmitter construction consists of a front plate 10 formed as indicated of sheet metal, and supporting centrally from its front face a mouthpiece 11 screwed therein. The edge of the front plate 10 is flanged as indicated at 10^a to support the inclosing shell 12, which is fastened to the front plate by suitable screws in a manner well known in the art. The flange 10^a is provided at diametrically opposite portions with inturned flanges 10^b, to which the bridge 13 is screwed as indicated.

The variable resistance element consists essentially of a cup 14 having a central boss 15, into which is threaded a stud 16, projecting rearwardly from the cup. The circular wall of the cup is internally threaded and engages a threaded ring 17, between which and the cup the rear electrode 18 is clamped. The outer end of the threaded ring 17 is engaged by the clamping ring 19 provided with an inturned outer flange for

engaging the outer portion of the delicate mica diaphragm 20 of the variable resistance element and holding it securely against the outer edge of the ring 17. Centrally located in the diaphragm 20 is a screw stud 21, which has rigidly secured to its inner end a metal disk 22, which in turn has secured to its inner face the front electrode 23 of the variable resistance element. Located outside of the diaphragm 20 is a dished spring washer 24, circular in form as shown in Fig. 4, and made of sufficiently thin spring material, such as brass, German silver or the like so that when it is forcibly clamped against the spacing washer 25 by the nut 26 it will exert a uniform spring tension circumferentially on the diaphragm 20 just inside of the periphery of the disk 22, and thus securely hold the diaphragm at the point where the clamping action is needed without, however, exerting such a rigid clamping effect as to in any way interfere with the proper operation of the diaphragm. Furthermore, the clamping action is uniformly distributed and is found to give an improved articulation as compared with the rigid clamping construction commonly in use, and furthermore, the tone produced is not as harsh with my construction as with the rigid clamping construction referred to.

The stud 16 projecting from the resistance element is mounted in the bridge 13 as follows: A first bushing 27 is supported near the middle portion of said bridge and insulated therefrom, being held in place by a clamping nut 28. This bushing carries a set screw 29, which engages a second bushing 30 contained in the first bushing, and holds said second bushing in desired longitudinal adjustment around the stud 16. A slight clearance is made in the bushing 30 around the stud 16 for purposes of adjustment, and when the parts are properly adjusted this space is filled wholly or in part with solder or cement 31, which rigidly secures the stud 16 to the bushing 30. This particular construction does not form a part of my present invention as it is the subject matter of a pending application, Serial No. 85,246, filed March 20, 1916, and I do not therefore claim this construction in the present application.

The screw stud 21 projects through the central portion of the main diaphragm 32 and is clamped thereto by a nut 33 carried by the outer end of said screw stud, the connector 34 being clamped between the main

diaphragm and the nut 26. The main diaphragm has its outer edge slightly dished as indicated in Fig. 1, so that for a short distance from the outer edge the diaphragm 5 constitutes a portion or frustum of a cone of large angle, the remaining portion of the diaphragm being substantially flat. The edge of the diaphragm rests against a ring of insulating material 35, such as mica or 10 empire cloth, and this insulating material in turn rests against a comparatively large ring 36 of lead, or non-resilient material. This lead ring is made slightly thicker than it is to be in the transmitter, and is forced into 15 place in the flange 10^a by means of a tool having a perfectly flat face, in a powerful press, the effect being to produce at the same time a perfectly flat surface for receiving the ring 35 and compress the lead of the 20 ring so as to wedge it into place in the flange 10^a. To insure that the ring 36 is securely held in place against accidental displacement which might result by careless handling of the assembled transmitters, it is 25 preferable to employ a suitable cement between the front plate 10 and the ring, as for example, Sterling insulated varnish, which I find, when properly applied, securely holds the ring against any handling 30 to which the transmitter may be subjected.

The lead ring referred to is for the following purpose: In constructing transmitter fronts from sheet material as is now common practice, the thickness of the material 35 can not be great if the metal is to be properly formed by the dies. As a result the front plates readily vibrate under the influence of external noises, and these vibrations are communicated directly to the main 40 diaphragm, where the telephone construction is such that the main diaphragm rests directly against the front plate or is separated therefrom only by means of hard and resilient material. By my construction the 45 relatively heavy lead ring serves in large measure to prevent the setting up of these vibrations by materially increasing the effective mass of the front plate, and furthermore, any vibrations that may be set up in the front plate are not communicated to the main diaphragm, for the reason that the material of the ring 36 is non-resilient, and has no spring or tendency to vibrate. The lead ring therefore serves to form an inert 50 or dead cushion for the main diaphragm against the effect of noises which may surround the transmitter. The shape of the main diaphragm serves in effect to make the diaphragm a spring, and at the same time 55 gives a large diameter vibration fulcrum to the diaphragm, which permits its ready vibration when sound waves are projected against it through the mouthpiece 11. I have found that with the same external di- 60 ameter by increasing the diameter of the

flat part of the diaphragm so that the angle of the dished part is reduced, the volume of sound produced by the transmitter is increased, but that the articulation is not quite as good, whereas by having the dished part 70 flatter the articulation is improved and the volume of the sound produced is somewhat lessened. The proportion shown has been found to give the best results for general purposes. 75

When the transmitter is completely assembled the connector 37 clamped under the nut 28 is connected to the binding post 38, and the connector 34 is connected with the binding post 39, these binding posts being 80 carried by and insulated from the bridge 13, dampening springs 40 secured to the bridge rest against the rear face of a disk 41 of insulating material, such as empire cloth, which is placed against the rear face of the 85 main diaphragm, and all of the parts are inclosed in the shell 12 as indicated in Fig. 1.

As a result of my present invention I find that my improved transmitter operates more quietly and effectively on account of the construction of the main diaphragm and its seat and the manner of clamping the diaphragm of the resistance element, and at the same time the construction is cheaper than many constructions heretofore employed. It is to 95 be borne in mind that the resistance element may be mounted from the bridge in any desired manner, and in connection with my present invention, therefore, I do not limit myself to any particular bridge mounting 100 arrangement, the present construction merely being shown as typical of one such arrangement.

The carbon granules commonly employed in telephone transmitters are not shown in 105 the drawings, as their use in variable resistance elements is well known in the art and they require no special illustration or description.

What I claim is:

1. In a telephone transmitter, the combination of a sheet metal front plate, a ring of heavy non-resilient material secured to the rear face of said front plate, a diaphragm resting against the rear face of said 115 ring, a bridge secured to the front plate, and a variable resistance element mounted between said bridge and said diaphragm.

2. In a telephone transmitter, the combination of a sheet metal front plate, a lead 120 ring secured to said front plate, a diaphragm pressed against said ring, a bridge carried by said front plate, and a variable resistance element mounted between said bridge and said diaphragm.

3. In a telephone transmitter, the combination of a sheet metal front plate, a ring of heavy non-resilient material secured to the rear face of said front plate, a diaphragm resting against the rear face of said 130

- ring, a bridge secured to the front plate, and a variable resistance element mounted between said bridge and said diaphragm, said variable resistance element comprising a cup, 5 a thin diaphragm inclosure for said cup, a rigid disk on one side of said thin diaphragm, and a dished clamping disk of thin spring metal held against the other side of said thin diaphragm.
- 10 4. In a telephone transmitter, the combination of a sheet metal front plate, a lead ring secured to said front plate, a diaphragm pressed against said ring, a bridge carried by said front plate, and a variable resistance element mounted between said bridge and 15 said diaphragm, said variable resistance element comprising a cup, a thin diaphragm inclosure for said cup, a rigid disk on one side of said thin diaphragm, and a dished 20 clamping disk of thin spring metal held against the other side of said thin diaphragm.
5. In a telephone transmitter, the combination of a sheet metal front plate, a ring 25 of heavy non-resilient material secured to the rear face of said front plate, a diaphragm resting against the rear face of said ring, a bridge secured to the front plate, and a variable resistance element mounted 30 between said bridge and said diaphragm, said diaphragm being slightly dished around its outer edge from the plane of said diaphragm.
6. In a telephone transmitter, the combination of a sheet metal front plate, a lead 35 ring secured to said front plate, a diaphragm pressed against said ring, a bridge carried by said front plate, and a variable resistance element mounted between said bridge and 40 said diaphragm, said diaphragm being slightly dished around its outer edge from the plane of said diaphragm.
7. In a telephone transmitter, the combination of a sheet metal front plate, a ring 45 of heavy non-resilient material secured to the rear face of said front plate, a diaphragm resting against the rear face of said ring, a bridge secured to the front plate, and a variable resistance element mounted 50 between said bridge and said diaphragm, and cement between said ring and said front plate for holding said ring in place.
8. In a telephone transmitter, the combination of a sheet metal front plate, a lead 55 ring secured to said front plate, a diaphragm pressed against said ring, a bridge carried by said front plate, and a variable resistance element mounted between said bridge and said diaphragm, and cement be- 60 tween said ring and said front plate for holding said ring in place.
9. In a telephone transmitter, the combination of a sheet metal front plate, a ring 65 of heavy non-resilient material secured to the rear face of said front plate, a dia-
- phragm resting against the rear face of said ring, a bridge secured to the front plate, and a variable resistance element mounted between said bridge and said diaphragm, said ring having a compressed rear surface 70 affording a true seat for said diaphragm.
10. In a telephone transmitter, the combination of a sheet metal front plate, a lead ring secured to said front plate, a diaphragm pressed against said ring, a bridge carried by 75 said front plate, and a variable resistance element mounted between said bridge and said diaphragm, said ring having a compressed rear surface affording a true seat for said diaphragm.
11. In a telephone transmitter, the combination of a sheet metal front plate, a ring of heavy non-resilient material secured to the rear face of said front plate, a diaphragm resting against the rear face of said ring, a bridge secured to the front plate, and a variable resistance element mounted between said bridge and said diaphragm, said ring being held in place in said front plate by compression of the material in said ring. 80
12. In a telephone transmitter, the combination of a sheet metal front plate, a lead ring secured to said front plate, a diaphragm pressed against said ring, a bridge carried by said front plate, and a variable resistance element mounted between said bridge and said diaphragm, said ring being held in place in said front plate by compression of the material in said ring. 95
13. In a telephone transmitter, the combination of a sheet metal front plate, a ring of heavy non-resilient material secured to the rear face of said front plate, a diaphragm resting against the rear face of said ring, a bridge secured to the front plate, and a variable resistance element mounted between said bridge and said diaphragm, said diaphragm having a small amount of its surface adjacent its outer edge bent forwardly into the frustum of a cone of large angle. 100
14. In a telephone transmitter, the combination of a sheet metal front plate, a lead ring secured to said front plate, a diaphragm pressed against said ring, a bridge carried by said front plate, and a variable resistance element mounted between said bridge and said diaphragm, said diaphragm having a small amount of its surface adjacent its outer edge bent forwardly into the frustum of a cone of large angle. 115
15. In a telephone transmitter, the combination of a front plate, a bridge secured to the front plate, a variable resistance element mounted upon said bridge, and a diaphragm connected with said variable resistance element, said diaphragm having its edge surface bent forwardly into the frustum of a cone of large angle resting loosely against the rear of said front plate. 125
16. In a telephone transmitter, the com- 130

bination of a front plate, a bridge secured to the front plate, a variable resistance element mounted upon said bridge, a diaphragm connected with said variable resistance element, said diaphragm having its edge surface bent forwardly into the frustum of a cone of large angle resting loosely against

the rear of said front plate, and a ring of hard insulating material between the edge of said diaphragm and said front plate. 10

In witness whereof, I hereunto subscribe my name this 22nd day of February A. D. 1916.

ARTHUR ROBERT KAHL.
